UNITED STATES PATENT OFFICE

JOHN R. MYERS, OF ELIZABETH, NEW JERSEY, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed March 14, 1928. Serial No. 261,665.

My invention relates to railway traffic controlling apparatus, and particularly to apparatus of the type comprising train carried governing means controlled by energy received from the trackway. More particularly my present invention relates to the trackway portion of such apparatus.

With apparatus of the type described, it is customary to supply the train controlling current directly to the track rails, which are divided to form track sections. The train controlling current, in at least one form of system at present in use, is delivered by a coding device, one of which is usually provided for each track section. One feature of my invention is the provision of circuits for supplying train controlling current from a single coding device to a plurality of track sections without requiring the use of additional line wires.

Another feature of my invention is the arrangement of circuits in such manner that train controlling current is supplied to the rails of each section only when a train actually occupies such section.

I will describe one form of apparatus embodying my invention, and will then point out the novel features thereof in claims.

In the accompanying drawings, Fig. 1 is a diagrammatic view illustrating one form of trackway apparatus embodying my invention. Figs. 2 and 3 are diagrammatic views showing modified forms of a portion of the apparatus illustrated in Fig. 1 and also embodying my invention.

Similar reference characters refer to similar parts in each of the three views.

Referring first to Fig. 1, the reference characters 1 and 1^a designate the track rails of a stretch of railway track over which traffic normally moves in the direction indicated by the arrow. These track rails are divided, by means of insulated joints 2, to form a plurality of successive blocks of railway track only one of which blocks, A—D, is shown complete in the drawings. It is sometimes desirable to divide the rails of each block into a plurality of sections, and block A—D is so divided by additional insulated joints 2 into track sections A—B, B—C, and C—D.

Each track section is provided with a track relay, designated by the reference character R with an appropriate exponent, and having two windings 7 and 8. One winding, 7, of each track relay R is constantly connected across the rails adjacent one end of the associated section, and the remaining winding 8 is constantly supplied with alternating current from the secondary of a line transformer designated by the reference character Q with an exponent corresponding to the location. The primary of each transformer Q is supplied with alternating current from a suitable source of energy such as an alternator G over line wires 3 and 3^a. Track circuit current for controlling the track relays is at times supplied to the rails of each section from a track transformer having a secondary 4 constantly connected across the rails in series with the usual impedance 6. Current is at times supplied to the primary of each transformer T in a manner which will be explained in detail hereinafter.

Block A—D is provided with a line relay designated by the reference character H^A. Each block is provided with a corresponding relay, but the line relay for the section to the right of point B is omitted from the drawing for the sake of simplicity. Line relay H^A is at times supplied with energy from transformer Q^D over a circuit which may be traced from the left-hand terminal of this transformer, through wires 11, and 12, contact 13 of an approach relay F^D, wires 14 and 15, front contact 16 of track relay R^C, wires 17 and 18, front contact 19 of track relay R^B, wire 20, front contact 21 of track relay R^A, wire 22, winding of relay H^A, wire 23, front contact 24 of track relay R^A, wire 25, front contact 26 of track relay R^B, wires 27 and 28, front contact 29 of track relay R^C, and wires 30, 31, 32, 33, 34 and 35, back to transformer Q^D. It will be plain from an examination of the drawing that the circuit just traced for line relay H^A comprises a pair of line wires extending throughout the block and including front contacts on each of the track relays in the block. When this circuit is closed, the line relay H^A is energized but this relay is de-

energized when the train occupies any portion of block A—D.

Each block is provided with a polarized relay designated by the reference character L with an appropriate distinguishing exponent, and controlled in accordance with traffic conditions in advance. The control of the polar relays L forms no part of my present disclosure and the circuits of these relays have been omitted from the drawing to simplify the disclosure. For present purposes it is sufficient to state that each relay L is normally energized in the normal direction so that its polar contacts are swung to the left. Each relay L, however, is de-energized when the corresponding block or the block next in advance is occupied; and is energized in the reverse direction so that its polar contacts are swung to the right, when the corresponding block and the block next in advance are unoccupied but the second block in advance is occupied. Associated with each polarized relay L is a slow acting repeater relay designated by the reference character P, with an exponent corresponding to the location. Referring particularly to relay P^A, the circuit for this relay may be traced from the left-hand terminal of the secondary of transformer Q^A, through wires 36 and 37, contact 38 of relay L^A in its normal or reverse position, wire 39, winding of relay P^A, and wires 40, 40^a and 41 back to transformer Q^A. It will be plain, therefore, that relay P^A is energized when relay L^A is energized in either direction, but that relay P^A is de-energized when relay L^A is de-energized.

Each block is provided with a trackway signal, designated by the reference character S with an appropriate distinguishing exponent. In the form here shown, each signal S is located adjacent the entrance end of the corresponding block and comprises an upper three-position semaphore blade and a lower two-position semaphore blade, but this particular form and arrangement of signals is not essential. Each signal S is controlled by the associated relay H and by the associated polarized relay L and repeater relay P. Referring for example, to signal S^A, as shown in the drawing, relays H^A and P^A are both energized, and relay L^A is energized in the normal direction. Under these conditions, current flows from the left-hand terminal of the secondary of transformer Q^A, through wires 36, 42 and 43, front contact 44 of relay H^A, wire 45, front contact 46 of relay P^A, wire 47, normal contact 48 of relay L^A, wire 49, operating mechanism of the upper blade of signal S^A and wires 50, 51 and 41 back to transformer Q^A. Under these conditions, the upper blade of signal S^A indicates proceed, and since the operating circuit for the lower blade of the signal is open, the latter blade indicates stop. I will now assume that relay L^A is energized in the reverse

direction and that relays H^A and P^A are closed. Under these conditions, current flows from the secondary of transformer Q^A, through wires 36, 42 and 43, front contact 44 of relay H^A, wire 45, front contact 46 of relay P^A, wire 47, reverse contact 48 of relay L^A, wire 52, operating mechanism of the lower blade of signal S^A, and wires 50, 51 and 41 back to transformer Q^A. At the same time, current flows from the secondary of transformer Q^A, through wires 36, 42 and 43, front contact 53 of relay H^A, wires 54 and 55, reverse contact 56 of relay L^A, wires 57 and 60, operating mechanism of the upper blade of signal S^A and wires 50, 51 and 41 back to transformer Q^A. Under these conditions the lower blade of signal S^A indicates proceed and the upper blade of this signal indicates caution.

If relay L^A is de-energized, relay P^A will also be de-energized, and if under these conditions, relay H^A is energized, current will flow from the secondary of transformer Q^A, over wires 36, 42 and 43, front contact 53 of relay H^A, wires 54 and 58, back contact 59 of relay P^A, wires 60^a and 60, operating mechanism of the upper blade of signal S^A, and wires 50, 51 and 41, back to transformer Q^A. Under these conditions, then, the lower blade of signal S^A indicates stop and the upper blade of signal S^A indicates caution. When relay H^A is de-energized, as by the presence of a train in block A—D, all of the operating circuits of signal S^A are open and both blades of this signal indicate stop.

Associated with each track section is a polarized approach relay, located adjacent the exit end of the section, and designated by the reference character F with a distinguishing exponent. Each approach relay F in the form here shown comprises two windings 9 and 10, one of which, 10, is constantly supplied with alternating current from the secondary of the adjacent line transformer Q. The remaining winding 9 of each approach relay F is at times supplied with alternating current of one relative polarity or the other from an associated auxiliary transformer designated by the reference character W with an exponent corresponding to the location. The primary of each transformer W is constantly supplied with alternating current from the adjacent line transformer Q. Referring first to relay F^B, winding 9 of this relay is provided with a circuit which may be traced from the upper terminal of the secondary of transformer W^A, through wire 61, front contact 62 of relay R^A, wire 63, winding 9 of relay F^B, and wire 64 back to the midpoint of the secondary of transformer W^A. This circuit is closed when track relay R^A is energized, under which conditions the current supplied to relay F^B is of such polarity that the relay is energized in its normal direction so that its contacts are swung to the left. When relay

100

105

110

115

120

125

130

R^A is de-energized, current flows from the midpoint of the secondary of transformer W^A , through wire 64, winding 9 of relay F^B , wire 63, back contact 66 of relay R^A , and wire 65 to the lower terminal of the secondary of transformer W^A . Under these conditions, the polarity of the current supplied to relay F^B is such that the relay is energized in its reverse direction so that its contacts are swung 10 to the right.

When relay R^B is energized, and when relay F^B is energized in the normal direction, current is supplied from the left-hand terminal of the secondary of transformer W^B , 15 through wire 67, normal contact 68 of relay F^B , wire 118, front contact 69 of relay R^B , wire 70, winding 9 of relay F^C , and wire 71 back to the mid-point of the secondary of transformer W^B , and when this circuit is 20 closed relay F^C is energized in its normal direction. When relay R^B is de-energized, however, current from transformer W^B flows through wire 71, winding 9 of relay F^C , wire 70, back contact 73 of relay R^B , and wire 72 25 to the right hand terminal of the secondary of transformer W^B , and under these conditions, relay F^C is energized in the reverse direction. It should be pointed out that relay F^C is energized in the reverse direction when 30 relay R^B is de-energized, and is energized in the normal direction when relay R^B is energized provided relay F^B is then energized in the normal direction. When relay R^B is energized and relay F^B is energized in the reverse 35 direction or is de-energized, relay F^C is de-energized. The circuits for controlling relay F^D are similar to the circuits just traced for relay F^C and will be understood from the drawing without further explanation.

40 As shown in the drawing, the track is unoccupied so that all of the track relays R are energized. Relays F^B , F^C and F^D are all energized in the normal direction. Under these 45 conditions, track circuit current is supplied to the rails of each section in block A—D as follows:

Referring first to section A—B, the circuit for track transformer T^B may be traced from the secondary of transformer Q^B over wires 50 74 and 75, contact 76 of relay F^B , wire 77, front contact 78 of relay R^B , wire 79, primary 5 of track transformer T^D , wire 80, front contact 81 of relay R^B , wire 82, contact 83 of relay F^B , and wires 84 and 85 back to the 55 secondary of transformer T^B . This circuit includes two contacts 76 and 83 of the approach relay F^B , which are arranged to be closed when the relay is energized in its normal direction or is de-energized, but to be open when 60 the relay is energized in its reverse direction. The remaining track transformers T^C and T^D are provided with circuits similar to that traced for transformer T^B .

When a train enters the block A—D, relay R^A becomes de-energized, thereby energiz-

ing relay F^B in its reverse direction. As a result, the supply of the track circuit current to the rails of section A—B is discontinued because contacts 76 and 83 of relay F^B are now open. Since relay R^B is energized and since relay F^B is now energized in its reverse direction, relay F^C is de-energized, one circuit for this relay being open at normal contact 68 of relay F^B , and the other circuit being open at back contact 73 of relay R^B . 70 In similar manner relay F^D becomes de-energized when normal contact 119 of relay F^C opens. When the approach relay F^D becomes de-energized, the closing of back contact 89 sets into operation a code transmitter designated in general by the reference character K and comprising a motor M which operates three code wheels N^1 , N^2 and N^3 . Code wheel N^1 operates a contact 92, and code wheels N^2 and N^3 operate contacts 93 and 94 respectively, the contacts 92, 93 and 94 operating in such manner that when the motor M is operated, the contacts are alternately opened and closed at different frequencies. The circuit for motor M may be traced from the secondary of transformer Q^D , through wires 11, 86, 87 and 88, contact 89 of relay F^D , wire 90, motor M and wires 91, 33, 34 and 35, back to transformer Q^D . Contact 89 of relay F^D is closed when the relay is de-energized or is 95 energized in the reverse direction, and so motor M of code transmitter K is now energized.

The train controlling current consists of alternating current which is periodically varied by one of the contacts 92, 93 or 94 of the code transmitter K , depending upon traffic conditions in advance. For example, as shown in the drawing, relays R^D and P^D are both energized, and, assuming that the train occupies section A—B, the circuit for train controlling current passes from the secondary of transformer Q^D , over wires 11, 86, 87, 95 and 96, contact 94 of code transmitter K , wire 97 front contact 98 of relay P^D , wire 99, 100 front contact 100 of relay R^D , wire 101, contact 102 of relay F^D , wires 14 and 15, front contact 16 of relay R^C , wires 17 and 120, reverse contact 103 of relay R^B , wire 77, front contact 78 of relay R^B , wire 79, primary 5 of transformer T^B , wire 80, front contact 81 of relay R^B , wire 82, reverse contact 104 of relay F^B , wires 121 and 28, front contact 29 of relay R^C , and wires 30, 31, 32, 33, 34 and 35, back to the secondary of transformer Q^D . It 115 will be plain then that as soon as a train enters the block, the code transmitter K commences to operate, and that with relay F^D de-energized, the train controlling current is delivered to the line wires normally used to control the relay H^A . The de-energization of relay R^A disconnected relay H^A from these wires when the train entered the block. It 120 will also be seen that as long as the train occupies section A—B, train controlling cur- 125 130

rent is supplied from these line wires over reverse contacts of relay F^B and front contacts of relay R^B to the rails of section A—B through transformer T^B . When the train enters section B—C, relay R^B opens, thereby interrupting the supply of the train controlling current to the rails of section A—B. At the same time the closing of back contact 73 of relay R^B energizes relay F^C in the reverse direction. When this occurs, train controlling current is supplied to primary 5 of transformer T^C over circuits similar to those already traced for transformer T^B . Under these conditions, then, train controlling current is supplied to the rails of section B—C in advance of the train. Similarly, when the train enters section C—D, the de-energization of relay R^C interrupts the supply of train controlling current to section B—C and energizes relay F^D in the reverse direction. With relay F^D energized in the reverse direction, contact 89 of this relay is still closed, and contact 111 is also closed, so that train controlling current is then supplied to the rails of section C—D.

When relay R^B became de-energized, a circuit was closed for transformer T^B , from secondary of transformer Q^B , through wires 74, 180, 112, 113 and 114, back contact 115 of relay R^B , wire 79, primary 5 of transformer T^B , wire 80, back contact 116 of relay R^B , and wires 117, 118 and 85, back to transformer Q^B . When the rear of the train passes out of section A—B, then, relay R^A will become energized, thereby energizing relay F^B in the normal direction and connecting relay H^A with wires 20 and 25, but front contacts 19 and 26 of relay R^B are now open so that relay H^A remains de-energized. In similar manner when a train passes out of section B—C, current supplied to transformer T^C over back contacts 122 and 123 of relay R^C , energizes relay R^B , thereby picking up relay F^C in the normal direction, but relay H^A is still de-energized because front contacts 16 and 29 are open. When the train finally passes out of section C—D, the next impulse of train controlling current supplied to section C—D energizes relay R^C . As a result, relay F^D becomes energized in the normal direction and contact 89 opens to stop the code transmitter K, thereby restoring the apparatus to the condition in which it is shown in the drawing.

In describing the operation of the code transmitter when supplying train controlling current, I assumed that relays R^D and P^D were both energized. It should be pointed out, however, that if relay R^D is energized and relay P^D is de-energized, when the train enters block A—D, the train control circuit is similar to the one traced hereinbefore except that wire 96 is connected with wire 99 over contact 93 of code transmitter K, wire 106 and back contact 107 of relay P^D instead

of through contact 94 of transmitter K. In similar manner if relay R^D is de-energized, wire 96 is connected with wire 101, through contact 92 of code transmitter K, wire 108, and back contact 100 of relay R^D . It will therefore be seen that the code transmitter K operates to supply the rails of the block with train controlling current which is periodically varied at different frequencies depending upon the condition of traffic in advance of the block.

It should be observed that with the apparatus illustrated in Fig. 1 when a train enters block A—D, relay R^A is first de-energized, relay F^B then becomes energized in its reverse direction, relay F^C then becomes de-energized and finally relay F^D becomes de-energized. It will be seen that these relays operate in cascade and that not until the last relay in the series has become de-energized can the code transmitter K commence to operate to deliver train controlling current to the rails of the block. Under some conditions local circumstances might make it desirable to have a large number of sections in a block, thus necessitating a correspondingly large number of approach relays F. With the apparatus shown in Fig. 1, these relays would operate in cascade so that the entire series of relays would have to operate before train controlling current would be supplied to the rails. It might happen that the time interval thus introduced would be sufficient to cause improper operation of the train carried governing means.

The approach relays F may be operated in multiple instead of in cascade by the expedient illustrated in Fig. 2. In the modification here shown, the circuits for relay F^B are the same as in Fig. 1. Relay F^C , however, is energized in the normal direction when relay R^B is energized and when relay F^B is energized in the normal direction by current from transformer W^A , over a circuit which passes from the secondary of transformer W^A , through wire 61, front contact 62 of relay R^A , wires 63 and 67, normal contact 68 of relay F^B , wire 118, front contact 69 of relay R^B , wire 70, winding 9 of relay F^C , wires 71 and 130, front contact 131 of relay R^A , and wire 32 back to the midpoint of the secondary of transformer W^A . The circuit for energizing relay F^C in its reverse direction is the same as shown in Fig. 1.

The circuits for operating relay F^D are similar to those described for relay F^C and will be understood without further explanation. With this arrangement it will be seen that under normal conditions each of the approach relays F is energized in its normal direction by current supplied from transformer W^A , over front contacts of relay R^A . When a train enters block A—D, then, relay F^B immediately becomes energized in the reverse direction and the remaining approach

relays immediately become de-energized. Approach relays F control the supply of the train controlling current to the rails in the same manner as in Fig. 1 and the operation of the apparatus as a whole will be understood without tracing it in detail. It should be pointed out, however, that with apparatus shown in Fig. 2, the time interval introduced by the cascade control of relays F in Fig. 1 is eliminated.

Referring now to Fig. 3, the apparatus is similar to that shown in Figs. 1 and 2 with the exception that the approach relay F^B is a neutral relay instead of a polarized relay. When relay R^A is energized, the secondary of transformer W^A is connected directly with the winding of relay F^B over front contacts 62 and 124 of relay R^A . Furthermore, when relay R^B is energized, the primary 126 of an insulated transformer Z^1 is connected, through front contacts 69 and 73 of relay R^B , in parallel with relay F^B . The secondary 127 of the insulated transformer Z^1 is connected directly with winding 9 of relay F^C and the current supplied to relay F^C under these conditions energies relay F^C in the normal direction. When relay R^B is de-energized, current is supplied from transformer Q^B , over back contacts 69 and 73 of relay R^B to primary 126 of insulated transformer Z^1 and under these conditions relay F^C is energized in the reverse direction. The circuits for relay F^D are similar to those just traced for relay F^C and the operation of this relay will be understood without tracing its circuits in detail. When relays F^B and R^B are energized, the primary 5 of transformer T^B is connected, over front contacts 78 and 81 of relay R^B , and front contacts 135 and 136 of relay F^B with the secondary of transformer Q^B so that under these conditions track circuit current is supplied to the rails of section A-B. When relay F^B is de-energized, however, the primary 5 of transformer T^B is connected with wires 17 and 28 over back contacts 135 and 136 of relay F^B , provided relay R^B is energized. The wires 17 and 28 are a part of the circuit for relay H^A as shown in Fig. 1 and hence train controlling current is supplied from these wires to the rails of section A-B when a train occupies the section. Finally when relay R^B is de-energized, track circuit current is supplied directly to primary 5 of transformer T^B from transformer Q^B , over back contacts 115 and 116 of relay R^B in the manner already described in connection with Fig. 1.

With the apparatus shown in Fig. 3, then, when a train enters section A-B, the de-energization of relay R^A de-energizes relay F^B and also de-energizes relay F^C and relay F^D , these relays opening immediately since they are not connected in cascade. It is understood that approach relays F^C and F^D in Fig. 3 control the supply of train controlling

current and track circuit current to the rails in the same manner as in Fig. 1, the non-essential portions of the apparatus being omitted from the drawing in order to simplify the disclosure.

In conclusion, it should be pointed out that with apparatus embodying my invention, the code transmitter is normally at rest and is set into operation only when a train enters the associated block. Furthermore, each track section is normally supplied with track circuit current and is supplied with train controlling current over the line wires normally used to control the H relays when and only when the train actually occupies the section. As soon as the front of the train passes out of a section, the de-energization of the track relay for the section next in advance discontinues the supply of train controlling current to the former section and supplies such former section with track circuit current.

Although I have herein shown and described only a few forms of railway traffic controlling apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a block of railway track having a plurality of successive track sections, a line relay, a device controlled by said line relay for governing traffic through said block, a source of energy, a circuit for at times connecting said source with said line relay, means effective when a train occupies said block to disconnect said relay from said circuit and for supplying train controlling current to at least a portion of said circuit, means also effective when the train occupies the block to supply train controlling current from said circuit to each section in advance of the train, and means for supplying track circuit current to each section in rear of said train.

2. Railway traffic controlling apparatus comprising a block of railway track having a plurality of successive track sections, a line relay, a device controlled by said line relay for governing traffic through said block, a source of energy, a circuit for at times connecting said source with said line relay, means effective when a train occupies said block to disconnect said relay from said circuit, a track relay for each section, an approach relay for each section each controlled in part by the track relay for the corresponding section, means controlled by each approach relay for at times supplying train controlling current to the associated section from said circuit, and means for supplying

track circuit current to each section when the track relay for the section next in advance is de-energized.

3. Railway traffic controlling apparatus comprising a block of railway track having a series of successive track sections, a track relay for each section, a line relay, a circuit for said relay controlled by all said track relays, a device controlled by said line relay for governing traffic through said block, an approach relay for each section, means for normally energizing all said approach relays in one direction, means effective when a train enters the first section in said block to energize the approach relay associated with said section in the opposite direction and to de-energize the remaining approach relays, means for successively energizing such remaining approach relays in the opposite direction as the train enters the corresponding sections, a code transmitter for supplying train controlling current to at least a portion of the circuit for said line relay when the last approach relay is de-energized or energized in such opposite direction, means for supplying train controlling current from said circuit to each section when the corresponding approach relay is energized in such opposite direction and the track relay for the section next in advance is energized, means for supplying each section with track circuit current when the track relay for the section next in advance is de-energized, and means for supplying each section with track circuit current when the corresponding approach relay is energized in said one direction and the track relay for the section next in advance is energized.
4. In combination, a rear, a middle and a forward section of railway track, a track relay for each section, means for normally supplying track circuit current to said rear and forward sections, a polarized approach relay for said middle section, means effective when the track relays for said rear and middle sections are energized to energize said approach relay in one direction, means effective when the track relay for said middle section is de-energized to energize said approach relay in the opposite direction, means controlled by said approach relay and by the track relay for said forward section for at times supplying said middle section with track circuit current, and means also controlled by said approach relay and by the track relay for the forward section for at other times supplying the middle section with train controlling current.
5. Railway traffic controlling apparatus comprising a block of railway track having a plurality of successive track sections, a track relay for each section, a line relay, a source of energy, a pair of line wires controlled by a front contact of each said track relay nor-

mally connecting said source with said line relay, a device controlled by said line relay for governing traffic through said block, means effective when a train occupies the block for supplying train controlling current to each section in advance of said train over at least a portion of said line wires, and means for supplying track circuit current to the rails of each section in rear of said train.

6. In combination with a block of railway track having a plurality of successive track sections, a track relay for each section, a polarized approach relay for each section, means for supplying the approach relay for the first section with current of one relative polarity or the other according as the associated track relay is energized or de-energized, means for supplying each of the remaining approach relays with current of one relative polarity when the associated track relay is energized provided the track relay for said first section is also energized, means for supplying each of said remaining approach relays with current of the opposite relative polarity when the corresponding track relay is de-energized, and means controlled in part by each approach relay for at times supplying the associated section with train controlling current and for at other times supplying the associated section with track circuit current.

7. In combination with a block of railway track having a plurality of successive track sections, a track relay for each section, a polarized approach relay for each section, means for energizing the approach relay for the first section in the normal or reverse direction according as the associated track relay is energized or de-energized, means for energizing each of the remaining approach relays in the normal direction when the corresponding track relay is energized and the approach relay for the section next in rear is energized in the normal direction, means for energizing each of said remaining approach relays in the reverse direction when the corresponding track relay is de-energized, and means controlled in part by each approach relay for at times supplying the associated section with train controlling current and for at other times supplying the associated section with track circuit current.

8. In combination with a block of railway track having a plurality of successive track sections, a track relay for each section, a polarized approach relay for each section, means for energizing the approach relay for the first section in the normal or reverse direction according as the associated track relay is energized or de-energized, means for energizing each of the remaining approach relays in the normal direction when the corresponding track relay is energized and the approach relay for the section next in rear is energized in the normal direction provided

the track relay for said first section is also energized, means for energizing each of said remaining approach relays in the reverse direction when the corresponding track relay is de-energized, and means controlled in part by each approach relay for at times supplying the associated section with train controlling current and for at other times supplying the associated section with track circuit current.

In testimony whereof I affix my signature.

JOHN R. MYERS.
